UNITED STATES PATENT OFFICE.

EUGENE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR GUN MOUNTING, LAYING, AND SIGHTING FOR ARTILLERY ON AEROPLANES.

Application filed June 30, 1923, Serial No. 648,833, and in France May 3, 1923.

In the different constructional forms of the invention described in my U. S. Patent No. 1,583,858, dated May 11, 1926, and entitled "Gun mounting, laying and sighting 5 arrangement for artillery on aeroplanes," it has been assumed that the firing was effected from a gun mounted on an aeroplane which was flying at a determined altitude and travelling in a straight line in the vertical plane passing through the target to be hit.

The present invention consists in different constructional forms of the main invention hereinbefore referred to, which shall be applicable in the case when the aeroplane flies 10 at a constant altitude but in a vertical plane, which, instead of passing exactly through the target, is at a certain distance therefrom.

In order to allow of accurate firing under these conditions according to the present invention the mounting is arranged in such a manner that the sighting apparatus comprised therein may be oriented during flight so as to be located within the inclined plane passing through the line of flight and the 15 target. Further, the mounting comprises the apparatus necessary for the automatic correction which should be given to the laying of the gun, in order to take account of the inclination of the sighting apparatus due 20 to the distance of the target from the vertical plane through the line of flight.

The invention will be readily understood by reference to the accompanying drawings illustrating three embodiments of the present 25 invention, and wherein—

Figures 1 to 8 represent an arrangement of the mounting, of the gun-laying mechanism and, the sighting apparatus and also comprising the new means hereinbefore referred to.

Figure 1 is a plan of the improved mounting partly in section, the gun being shown in a vertical position.

Figure 2 is a partial sectional elevation 40 taken on the line 2—2 of Fig. 1, the gun being shown in an inclined position for firing in the direction of flight of the aeroplane.

Figure 3 is a partial sectional elevation 45 taken on the line 3—3 of Fig. 1.

Figure 4 is a sectional elevation analogous to Fig. 3, but showing the parts in a different position.

Figure 5 is a sectional plan of a detail on a larger scale.

Figures 6 and 7 are sections taken respectively on the lines 6—6 and 7—7 of Fig. 5.

Figure 8 is a diagram explaining the working of a part of the apparatus.

Figures 9 to 18 inclusive, show a second embodiment of the present invention.

Figures 9 and 10 illustrate the arrangement of the mounting respectively in plan partly in section, and in elevation, partly in section, Fig. 10 being on the line 10—10 of Figure 9;

Figures 11 and 12 are transverse sections on the line 11—11 of Figure 10 respectively, showing the parts in two different working positions;

Figure 13 shows on an enlarged scale, a 70 sectional elevation of a detail taken on line 13—13 of Figure 9;

Figure 14 is a partial section of a detail taken on the line 14—14 of Figure 13;

Figures 15 and 16 are detail views partly 75 in section of the one-way clutch mechanism which may be employed;

Figures 17 and 18 are detail sectional views illustrating means for imparting an initial deviation to the reflecting prism of 80 the sighting apparatus;

Figures 19 to 23 inclusive, illustrate another embodiment of the present invention;

Figure 19 is a plan view, partly in section;

Figure 20 is a longitudinal sectional elevation taken on the line 20—20 of Figure 19;

Figure 21 is a transverse section taken on the line 21—21 of Figure 19, in which the gun is shown with its axis in the horizontal position and the frame in which the cradle 90 oscillates is consequently shown in the vertical position;

Figure 22 is a section analogous to that of Figure 21 but the frame in which the cradle oscillates is in this view shown in horizontal 95 position, the cradle being shown as inclined transversely as within this frame;

Figure 23 is a sectional elevation of a detail of the mechanism for deviating the reflecting entry prism of the sighting apparatus; and

Figure 24 is a partial plan of a modification of the embodiment illustrated in Figures 19 to 23 inclusive.

The arrangement comprises, as in the constructional forms of Figs. 7 to 14 of my Patent No. 1,583,858, a frame A running by means of rollers a on a divided circular roll-

ing track A¹. A second frame B is suspended by means of trunnions b rotating in bearings on the first frame A, so that this second frame B can thus oscillate about the longitudinal axis of the first frame A. Within the frame B and about an axis perpendicular to the axis b—b, the cradle C of the gun is pivotally mounted by means of trunnions c. Thus the cradle C is mounted by means of a cardan suspension within a frame A, which is itself adapted to pivot about a vertical axis.

The arrangement likewise comprises a mechanism for pivoting the frame A so as to permit the latter to be displaced in such a manner that its longitudinal axis will lie within the vertical plane passing through the line of flight. This vertical plane of flight is inclined at the angle Δ to the axis x—x of the aeroplane (see Fig. 23 of the patent above referred to). In the new construction the above mechanism is arranged so that it may be actuated by the pilot, and with this object may comprise a pinion b' (Fig. 9) engaging with a toothed sector B¹ formed on the frame A. The mechanism for elevating the gun, by oscillation of the cradle C around the axis of the trunnions c, comprises two toothed sectors C¹, carried by the cradle and gearing with toothed wheels B² carried by a shaft B³ which is rotatably mounted in the frame B. The shaft B³ carries a helical wheel B⁴, which is operated as hereinafter described.

The mechanism for the transmission of movement to the helical wheel B⁴ is housed in the box D (Fig. 1) which acts as a support for the sighting apparatus E. The box support D is mounted by means of a socket d, in the bearing of one of the trunnions b of the frame B.

The support D for the sighting apparatus should be adapted to receive transverse inclinations at the same time as the cradle C, but this latter together with the frame B should always be adapted to receive transverse inclinations independent of the support D. A connection is established between the support D and the frame B, by means of an arm D¹, which is formed as a projection from the box D and is provided at its free extremity with a sector having helical teeth d¹, which gear with a worm A² rotatably mounted in the frame A in the plane which is normal to the longitudinal axis of the said frame and passes through the axis of the trunnions e of the cradle.

The arm D¹ has a trunnion D² engaging in one of the ends of a connecting rod F whose other end engages by means of a spherical bearing f, with a cylindrical stud g formed as a projection on a nut G guided in an arm C² rigidly connected with one of the trunnions e of the cradle C. The nut G is adapted to be displaced along a screw

C³, which is rotatably mounted in the arm C² and is operable by means of a hand-wheel c³.

By actuating the hand-wheel a² in such a manner as to rotate the worm A² to turn about its axis, the sector d¹ is displaced relative to the worm A², carrying along with it the arm D¹ and the support D, thereby causing the sighting apparatus to rotate about the axis of the trunnions b. At the same time the connection F—G effects the rotation of the frame B about the same axis b—b. Consequently the sighting apparatus and the gun are inclined, at the same time and through the same angle, around the axis of the trunnions b—b.

As in the constructional forms described in the United States patent referred to above, within the box support D are arranged mechanisms (see Fig. 23) comprising an elevation camoid and a camoid for the correction of the longitudinal action of the wind, in such a manner that the elevation given to the gun by the elevating mechanism produces a deviation of the line of sight, corresponding to the whole of the corrections for elevation and of the longitudinal corrections for wind.

The elevating mechanism of the cradle C comprises a shaft D⁵ which is rotatably mounted in the box D, and is operable by means of a hand-wheel d². This shaft D⁵ carries a bevel wheel d³ which transmits its movement to a pinion d⁴ keyed on a shaft D⁶ arranged along the axis of the trunnion b of the frame B. This shaft carries a worm D⁶ which gears with the worm wheel B⁴.

The movements of the shaft D⁴ are transmitted to the reflecting entry prism of the objective of the sighting apparatus, said movements being suitably corrected by the intervention of the camoids for elevation and for correction of the longitudinal action of the wind as in the constructional form of the Patent No. 1,583,858.

In the case when the aeroplane carries out its horizontal rectilinear flight in a plane which does not pass through the target, it is necessary that to the above corrections should be added those due to the distance between the target and the vertical plane through the line of flight.

In order that the cradle C should be brought to the position suitable for firing during flight, it is necessary to proceed as follows:

By operating the hand-wheel a² in the desired direction, the support D of the sighting apparatus and the cradle of the mounting C are brought together as a whole into the inclined plane through the line of flight and the target. The reflecting entry prism of the sighting apparatus being thus brought into this plane, it will remain there

during the course of the flight, whatever inclination may be afterwards given to the cradle around the axis of the trunnions c , and further whatever the transverse inclination which may be given to the cradle by its rotation about the axis of the trunnions b .

The angle i (Fig. 4) through which the whole of the sighting apparatus and the cradle has been turned, is equal to the angle i of inclination, with reference to the vertical plane, of the plane through the line of flight and the target. This angle i is imparted to the apparatus by the gun server, who operates the hand-wheel a^2 at the same time as he sights the target. This angle is indicated in a multiplied manner on a graph H (Figs. 2 and 5 to 7) mounted on a shaft h carried by the frame A. The shaft h is preferably arranged in the plane which is normal to the frame A and which passes through the axis of the trunnion b . A needle I is displaceably mounted on the graph H . The angular displacements imparted to the trunnion b are transmitted to the shaft h and to the needle I with a suitable multiplication, by means of a transmission comprising a toothed sector b^3 , rigidly connected to the trunnion b and gearing with a pinion a^3 , which is loose on a shaft carried by the frame A. This pinion a^3 is rigidly connected to a toothed wheel a^4 , which gears with a pinion h^1 keyed on the shaft h .

On the graph H concentric circles 1, 2, 3 etc. are traced corresponding to different altitudes of flight. The needle I carries a series of laterally projecting indicators I^1 , I^2 , I^3 etc. respectively movable over the circles 1, 2, 3 etc. On the periphery of the disc H is traced a scale H^1 whose graduations correspond to the different values of the angle of inclination i , which will be called hereinafter the "angle of deviation". In bringing the cradle and the sighting apparatus into the plane of deviation, the needle I has been displaced on the graph-disc H . This operation being performed, the gun-server, by operating the hand-wheel c^3 , imparts an inclination to the cradle by rotating the frame B about the axis of the trunnions b . The gun-server should incline the cradle, so that, by bringing the mark I^1 , I^2 etc., (corresponding to the altitude of flight) into coincidence with the corresponding graduation, he makes the inclination of the cradle correspond to the value of the angle i read on the scale H^1 . If, for example, the aeroplane flies at the altitude of flight corresponding to the circle 3 of the graph, the gun-server should continue to operate the hand-wheel c^3 until the moment when the mark I^3 on the needle I comes opposite the graduation on the circle 3, corresponding to the angle i of the deviation of the needle. If the needle I is at the

division 60, on the scale H^1 , it will be sufficient for the gun-server to bring the mark I^3 on to the division 60 read on the circle 3. It is assumed that the graph H is so arranged that the transverse inclination, thus given to the cradle with reference to the sighting apparatus, acts to suitably correct the elevation to correspond to the height of flight chosen.

A second correction is necessary in order to take account of the influence of the wind. This correction of transverse inclination of the cradle, which is obtained by the rotation of the frame B around the axis of the trunnions b , may be effected beforehand. The graph H carries as a projection a graduated sector H^2 whose graduations starting from a zero situated in h^2 , correspond respectively, on the left to the positive values of the action of the wind, and on the right to the negative values.

Knowing the direction and the value of the wind, the gun-server brings the corresponding graduation of H^2 opposite a fixed index a^5 . The whole of the curves traced on the graph H are thereby displaced through the desired angle with reference to the needle I. This displacement is effected by actuating the controlling knurled knob H^3 connected to a worm H^4 , which gears with helical teeth H^5 formed on the graph-disc H .

With the apparatus described, in order to effect firing from an aeroplane flying at a constant altitude in a vertical plane not passing through the target, it is necessary to effect the following operations:

As has been stated in the Patent No. 1,583,858, the gun-server first of all places into their desired positions the camoid for the correction of the elevation and the camoid for applying the correction due to the longitudinal action of the wind; the cradle is assumed to be inclined at the maximum angle (60° to the vertical for example) in the direction of flight. The graph H is operated by means of the knurled knob H^3 , in such a manner that the graduation of H^2 corresponding to the given value of the wind is brought opposite the fixed mark a^5 . The gun-server seeks to direct the line of sight of the sighting apparatus on to the target. If he does not see the target in the vertical plane of the line of flight, he acts upon the hand-wheel a^2 , in such a manner that the whole of the cradle, the frame B and the support D of the sighting apparatus has imparted to it the desired angle of deviation i in order that he may be able to see the target. From this time, the reflecting prism at the entrance of the objective of the sighting apparatus remains in the plane of deviation, that is to say the plane passing through the line of flight and the target. The angle i , at which the gun-server should incline the cradle and the support of the sighting ap-

paratus, is read by the deviation which has been given to the needle I upon the scale H^1 . The laying of the gun when effected by operating the elevating mechanism, so as to keep 5 the line of sight directed on to the target, should be corrected by taking into account the angle of deviation i and the given mean action of the wind. The first of these corrections i^1 is made automatically, in so far 10 as the gun-server operates the elevating mechanism in order to bring the line of sight on to the target. The correction is effected automatically for all changes of laying, starting from the time when the desired cor- 15 rection of deviation i^1 (read on the corresponding curve of the plate H^1) has been initially imparted to the cradle by the gun-server acting on the hand-wheel c^3 and thereby rotating the frame B around the axis of 20 the trunnions $b-b$. It has been seen that it was sufficient to bring the mark I^1, I^2, I^3 or the like on the needle I, corresponding to the altitude of flight onto that curve of the disc H^1 , which corresponds to the value of i . 25 During firing, it has been sufficient for the gun-server from that time to bring the line of sight on to the target by operating the elevating hand-wheel d^2 .

In the elevating movement, the gun, instead of pivoting in a plane, has its plane of rotation constantly deviated on account of the deviation of the axis of the trunnions c resulting from their connection with the trunnion D^2 through the connecting rod F, 30 the ball and socket joint f and the stud g .

In the diagram (Fig. 8) D^2 indicates the projection of the axis of the trunnion D^2 ; g indicates the projection of the axis of the stud g ; the distance D^2-g , or more exactly 35 the distance between the axis of D^2 and the centre of the ball and socket joint f is constant. If it is assumed that the vertical plane through the line of flight passes exactly through the target, the parts being then 40 arranged as is shown in Fig. 3, then no deviation should be given to the cradle by rotation around the axis of the trunnions $b-b$. It thereby follows that the cradle, in turning about the axis of the trunnions c , will turn 45 in a plane parallel to the connecting rod F. But if, on the contrary, the vertical plane through the line of flight does not pass through the target, so that it has been necessary to incline the frame B and the support 50 D in order to bring the line of sight into the plane of deviation which is inclined at the angle i relative to the vertical plane through the line of flight, then the parts will have initially taken the position indicated at Fig. 55 4 (the gun in this figure being shown as inclined at 60° to the vertical). Then, a rotation of the cradle around the axis of the trunnions c , with the object of elevating it, can only be effected in combination with a 60 forced and automatic secondary movement

of the frame B about the axis of the trunnions b ; the axis of the trunnion c on the right (Fig. 4) is in fact deviated angularly relative to the axis of the trunnion D^2 , and its projection has fallen from D^2 to c , 70 (Fig. 8) whereby the distance between the axis of c and the axis of g has been reduced. As the stud g necessarily turns around the axis of D^2 , there is thereby effected a rocking of the cradle around the axis of the trunnions b , which automatically corrects the 75 elevation for each position of the elevation.

Referring to the embodiment of the invention illustrated in Figures 9 to 18 inclusive, this arrangement comprises a frame A running by means of rollers a on a divided circular track A^1 . In bearings on this first frame A there is suspended by means of trunnions b , a second frame B which may thus oscillate around the longitudinal axis of 85 the frame A. Again as in the preceding example, the cradle of the mounting C is pivotally mounted by means of trunnions c within the frame B about an axis perpendicular to the axis of the trunnions b . The mechanism 90 which effects the turning of the frame A upon the track A^1 is similar to that described in the preceding example. The mechanism for inclining the gun, by oscillating the cradle C about the axis of the trunnions c , 95 comprises two toothed sectors C^1 , which are carried by the cradle and which gear with toothed wheels B^2 carried by the shaft B^3 rotatably mounted in the frame B. The shaft B^3 carries a worm wheel B^4 which 100 gears with a worm B^5 which is operable by means of a handle B^6 , the shank of the screw B^5 being mounted in a bracket which is rigidly connected with the frame B.

The box D which carries the sighting apparatus E is in this case rigidly connected with the frame B. The arrangement comprises a mechanism for effecting the inclination of the frame B by rotating it about the axis of the trunnions b , and thus bringing 105 the gun and the sighting apparatus into the desired position in order to take account of the angle of deviation i , that is to say of the angle formed between the vertical plane through the line of flight and the plane passing through this line and the target. This mechanism is arranged so that whatever 110 may be the inclination given to the gun, said mechanism effects the complementary correction due to the deviation. The said mechanism comprises a worm J rotatably mounted in a support J^1 suitably guided in a slide-way A^3 rigidly connected with the frame A, the said support J^1 being in engagement, by means of helical teeth j^1 , with a worm A^4 115 which is rotatably mounted in the frame A, and is adapted to be operated by means of a handle A^5 . The screw J is also in engagement with a sector with helical teeth B^7 , formed on a projection of the frame B; and 120

130

both the sectors j^1 and B^7 have their centres on the axis of the trunnions b . The shank of the worm J is articulated through a pin j , to a threaded rod J^2 which engages in a 5 nut K carried by one of the arms K^1 of a bell-crank lever K^1-K^2 pivotally mounted on a shaft A^6 carried by the frame A . The free extremity of the arm K^2 is connected at k^2 to one of the elements L of a connecting 10 rod of adjustable length $L-L^1$ of which the other element L^1 is articulated to a lever M which, by means of a one-way clutch mechanism will be hereinafter described in detail, engages on a shaft N rotatably mounted in 15 the box-support D . The shaft N carries a bevel wheel N^1 which is in engagement with a pinion O^1 keyed on a shaft O which is also rotatably mounted within the same support D . The shaft O carries, on the other hand, a 20 worm O^2 which engages with a worm sector P , which is guided by means of ribs p in the cap of the reflecting entry prism Q of the objective, the ribs p having their centre at the centre of this spherical cap. q is the 25 shaft which, through any suitable mechanism such as the camoids for elevation and for longitudinal corrections of the wind disclosed in my application referred to hereinbefore, receives angular deviations which im- 30 part to the prism Q the deviation for inclination and the deviation corresponding to the longitudinal action of the wind.

If the parts are in the position indicated in Figs. 9, 10 and 11, where the gun is inclined at 60° to the vertical and in the direction of flight, and if it is assumed that the aeroplane carries out its rectilinear horizontal flight in a plane which does not pass through the target, it is always convenient 40 to add to the usual corrections for elevation and for wind, those corrections which are due to the angular distance i between the target and the vertical plane through the line of flight.

To effect this, the worm J is first of all 45 acted upon, by means of its operating hand-wheel, and this movement displaces the frame B and with this latter, the support D of the sighting apparatus. But the movements of inclination thus imparted to the 50 frame B , and consequently also to the trunnions c of the cradle, are not transmitted in full to the reflecting entry prism Q . The screw J^2 moves the nut K and through the latter the bell-crank lever K^1-K^2 . The arm K^2 of the bell-crank lever causes a pull or a thrust as may be the case, upon the element L of the connecting rod $L-L^1$, and this movement of pulling or thrust is transmitted to 55 the lever M .

The variable corrections which have to be given to the elevation, to allow for the distance between the vertical plane of flight and the target, are brought about by the 60 variable deviation which is imparted to the

prism Q during the elevating movements. In order to effect these variable deviations of the prism Q a special gearing is provided between the shaft N and the axle Y (Figs. 13 and 14), which is connected with the movements of one of the trunnions c of the cradle. This special gearing comprises a shaft R which is rotatably mounted in the box D , and which has keyed thereon a toothed sector R^1 engaging with a pinion N^2 , 70 keyed on the shaft N . The sector R^1 has rigidly attached thereto a stud R^2 , which rotatably engages within the bearing s at one end of a connecting rod S , whose other end s^1 , is guided in a slideway y which is 75 rigidly connected with the axle Y , and is formed as an arc of the circle having its centre on the axis of the shaft R .

Normally that is to say in the case when the vertical plane through the line of flight 80 passes also through the target, the geometrical axis r of the stud R^2 is in the prolongation of the geometrical axis of Y and of the trunnions c of the cradle. If the vertical plane through the line of flight is at a distance from the target, then the sighting apparatus must be inclined into the plane of deviation by suitably operating the screw J , and this operation, as already explained, 85 imparts a displacement to the prism Q through the transmission $N-O^1-O-O^2-P$. The displacement given to Q at the same time effects a rotation of the sector R^1 and this causes the end s^1 of the connecting rod S to be displaced within the slideway y . 90 Then, instead of the shaft r being in the prolongation of the axis of the trunnion c it is raised relative thereto through an angle, which varies according to the angle of deviation i . If now with the object of firing, 95 the inclination of the gun is changed, by operating the elevating mechanism by means of the crank B^6 , this produces a rotation of the trunnion c , and consequently imparts a corresponding displacement to the shaft Y 100 and to the connecting rod S , and thereby effects a change of inclination of the shaft r and consequently a displacement of the prism Q through the transmission 105

$R^1-N^2-N-N^1-O^1-O-O^2-P$.

115

It follows therefrom that to each deviation of inclination of the gun there corresponds a displacement imparted to the reflecting entry prism Q of the sighting apparatus, 120 and this displacement of the prism causes the gun-layer to bring the line of sight on to the target by imparting an inclination to the frame B around the trunnions b by means of the hand-wheel A^5 .

In order that the shaft N may be rotated independently of the lever M during the movements transmitted to the prism Q by the shaft Y , it is necessary that the connection between M and N may be effected 125

130

through an automatic one-way clutch mechanism such for example as that represented in Figs. 15 and 16.

When the hand-wheel j^2 is operated in order to deviate the prism Q , the transmission $K-K^1-K^2-L-L^1-M$ is acted upon at the same time and consequently an angular deviation is transmitted to the shaft N and consequently the axis r of the stud R^2 will be raised by a quantity which varies according to the angle of deviation i . The complementary deviation thus given to the prism Q displaces the line of sight from the target. In order to take account of this complementary correction (this deviation being produced during the operation itself which consists in keeping the line of sight on the target), the gun-server has only to concern himself with returning the line of sight on to the target, this being effected by suitably operating the mechanism A^5 for the transverse inclination of the training of the gun. He is then assured of having effected, during this operation, the correction due to the deviation. Further he has automatically arranged the members in such a way that a variation in the inclination of the gun about the trunnions of the cradle causes him by means of an automatic deviation imparted to the prism Q , to effect the necessary corrections when he brings the line of sight back on to the target.

In order that the complementary corrections of deviation imparted to the prism Q , by the transmission $N-O^1-O-O^2-P$, may have the desired value corresponding to the altitude of flight chosen and to the mean action of the wind, the length of the connecting rod $L-L^1$ is suitably adjusted before firing, so that there is imparted to the prism Q an initial deviation which is a function of the altitude of flight and of the said action of the wind. The suitable adjustment of the length of the connecting rod $L-L^1$ can be effected, for example, by the means represented on Figs. 17 and 18. On a fixed rod T , carried by the box D , is slidably mounted a first index T^1 , which is also guided in a groove u , provided in a drum U , which engages as a nut on a screw-thread of the element L of the connecting rod; the drum U carries a scale u^1 graduated in altitudes of flight, and it will be seen that if this drum is rotated in such a manner as to bring the desired division of the scale u^1 opposite the mark T^1 , said drum will be displaced upon a first thread, then fixed, of the element of the connecting rod L , while the index T^1 will slide without turning on the rod T . This displacement will at the same time impart movement to a second drum V , in a groove v , of which there is engaged an index T^2 also sliding on the rod T . The drum V is graduated in wind corrections and engages as a nut on a screw-

thread of the element of the connecting rod L^1 . On account of the annular connection U^1 between the drum U and the drum V , an angular displacement of one drum with reference to the other is possible while any longitudinal displacement of one of the drums effects a corresponding displacement of the other. Finally when the desired graduation of the drum U has been brought opposite the mark T^1 , and then the desired graduation of the drum V opposite the mark T , then the length of the connecting rod $L-L^1$ has been modified by the total quantity desired, thus imparting to the prism Q an initial deviation corresponding to the altitude of flight chosen and to the actual value of the wind.

In the embodiment of the invention illustrated in Figures 19 to 23 inclusive, the installation comprises a frame A , running by means of rollers a on a circular rolling track A^1 . A frame B is mounted so as to oscillate by means of trunnions b within bearings, which are secured to the frame A and which are arranged along its small axis and the cradle C is mounted so that it may oscillate within the frame B by means of trunnions c arranged along an axis perpendicular to that of the trunnions $b-b$.

The mechanism for turning the frame A upon the track A^1 comprises a worm sector A^7 upon the frame A which sector is acted on by means of a worm A^8 , whose shank a^8 is journalled in fixed bearings A^9 and is actuated by a hand-wheel A^{10} .

The inclination of the gun is effected by oscillation of the cradle C within the frame B , around the axis of the trunnions c . For the variations of elevation, the frame B is caused to oscillate about the axis of the trunnions b by means of a mechanism which comprises a hand-wheel A^{11} rotatably mounted in the frame A , and on whose shank a^{11} is keyed a worn A^{12} in gear with a worm wheel A^{13} , keyed on a shaft a^{13} . This shaft a^{13} is rotatably mounted in the frame A and carries a toothed wheel A^{14} gearing with a toothed sector B^8 carried by the frame B .

The mechanism for the transverse inclination of the gun, by oscillation of the cradle C about the axis of the trunnions c , comprises an arm C^4 on the cradle C . This arm C^4 contains a spherical recess c^4 in which is engaged a spherical stud c^5 formed as a projection upon an arcuate slide-block C^5 , guided in a slideway of corresponding form B^9 on the frame B . The slide-block C^5 carries a second stud c^6 which is constantly maintained within an arcuate slideway X having its centre on the geometrical axis of the trunnions b . The slideway X is guided by means of two extensions X^1 upon ribs x^2 formed as projections upon levers X^2 keyed upon a shaft X^3 which is rotatably mounted within the support D for the sight.

ing apparatus E. One of the levers X^2 carries a worm sector with helical teeth X^6 engaging with a worm X^4 , whose shank is rotatably mounted in the support D and may be operated by a disc x^4 . The two levers X^2 are connected by a bridge x^3 carrying bearings in which there is rotatably mounted the shank of a worm X^5 adapted to be operated by a member x^5 ; this worm gears with a worm sector x , which is carried by the slideway X and which is concentric with the slideway x^2 . Upon the shaft X^3 is keyed a toothed sector X^7 (Fig. 23), gearing with a toothed wheel O^8 keyed on a shaft o^3 rotatably mounted in the supporting box D for the sighting apparatus; the wheel O^8 gears, in its turn, with a toothed sector O^4 loosely mounted upon a shaft o^4 and rigidly connected to a slideway P^2 oscillating around the said shaft and a second shaft o^5 arranged in the prolongation of the first; within the slideway P^2 is engaged a finger P^1 whose displacements actuate the movements of the reflecting entry prism Q of the sighting apparatus.

In the case when the aeroplane carries out its rectilinear horizontal flight in a vertical plane which does not pass through the target, the following operation should be carried out: the cradle and the gun being assumed to be in the position indicated in Fig. 20, where the plane through the vertical axis of the cannon is coincident with the plane of flight, then, in order to effect the laying of the gun, the hand-wheel x^4 is actuated, and this consequently operates the transmission $X^4-X^6-X^2-x^2$ which moves the slideway X so that it pivots about the shaft X^3 . In this movement, displacements are imparted to the studs c^6 and c^5 of the slide-block C⁵. Through the stud c^5 , the arm C⁴ of the cradle is itself displaced and this effects an oscillation of the whole of the gun and the cradle about the trunnions c. The gun-server continues to actuate the hand-wheel x^4 until he can see the target through the eye-piece of the telescope. The displacements of the cradle and of the telescope are effected simultaneously, the reflecting prism Q being moved by the finger P¹ which itself is actuated through the transmission $P^2-O^4-O^3-X^7-X^3$. Thus, in sighting on the target, the whole of the cradle and of the gun has been brought to the desired inclination corresponding to the deviation. Before firing, it remains to operate the elevating mechanism by means of a hand-wheel A¹¹. The desired elevation is given by means of the transmission A¹²-A¹³-A¹⁴-B⁸. By effecting the elevation in this manner the transverse inclination of the cradle C is corrected automatically by the oscillation about the trunnions c, caused by the action of the slideway X upon the stud c^6 , the slide-block C⁵, the

stud c^5 and the arm C⁴. In order to take account of the correction of transverse inclination to be given to the gun corresponding to a wind of determined value, the hand-wheel x^5 is actuated before firing, the displacements of this hand-wheel being adapted to be read on a scale arranged at a convenient position. By means of the transmission X⁶-x these displacements of the hand-wheel x^5 effect an inclination of the slideway X, and consequently act upon the stud c^6 , the slide-block C⁵ and through the latter upon the arm C⁴ of the cradle.

It is understood that the sighting apparatus as in the preceding examples, as well as in those described in the Patent No. 1,583,858 will be provided with apparatus for the correction of the elevation and of the deviations due to the longitudinal action of the wind. This apparatus may comprise a camoid Z (Fig. 23) constituting the corrector of elevation and a camoid constituting the corrector for the longitudinal action of the wind, and these correctors act automatically upon the reflecting prism of the sighting apparatus, in proportion as the gun-server operates the elevating mechanism; these two corrections are finally secured when after having given the desired elevation, the line of sight has been brought on to the target, by means of the elevating mechanism.

Figure 24 is a partial plan of a modification of the constructional form which has been just described. In this modification, the frame A may be given an oscillating movement about its longitudinal axis; with this object this frame is arranged as two elements; the frame A carrying the trunnions a^{14} and two carriages A¹⁵ in which the trunnions a^{14} are adapted to oscillate, a kinematic connection being provided which allows the oscillation about the trunnions a^{14} but effects a rigid connection between A and A¹⁵ during the movements of rotation on the rolling tracks A¹; this connection may consist, for example, of a worm A¹⁶ journaled in one of the carriages A¹⁵ and which is in engagement with a worm sector A¹⁷ carried by the frame A. This possible mobility of the frame A with reference to the carriage A¹⁵ permits if required of giving to the cradle a complementary transverse inclination, with the object of introducing additional corrections.

While three embodiments of the present invention have been described in detail and illustrated in the accompanying drawings, it is to be understood that the drawings are for purposes of illustration only and are not designed as a definition of the limits of the invention, reference being had for this purpose to the appended claims.

What is claimed is:—

1. In combination with an aeroplane, a

gun, a mount therefor, means for laying the gun, sighting apparatus for the gun, means for transversely inclining said gun and sighting apparatus into an inclined plane passing through the line of movement of the gun and the target, and supplemental means interposed between said gun and second named means for correcting the laying of the gun, whereby correction for the 5 inclination of said apparatus due to the 10 distance of the target from the vertical plane passing through the line of movement of the gun is secured.

2. In combination with an aeroplane, a 15 gun mounted on said aeroplane, training and elevating means for the gun, sighting apparatus for the gun, means for orienting said gun and sighting apparatus into an inclined plane passing through the line of 20 flight and a target, and supplemental means interposed between said gun and second named means for applying the necessary 25 correction to the inclination of the gun to take into account the deviation due to the 30 distance from the target of the vertical plane through the line of flight, said supplemental means including correction means for varying 35 the inclination of the gun in correlation with elevating movement of the gun.

3. An aeroplane gun mounting for laying a gun when the target lies in a plane at a 40 distance from the vertical plane through the line of flight comprising, in combination with a gun, gun laying means, sighting apparatus for the gun, means orienting said gun and 45 sighting apparatus during flight into the inclined plane passing through the line of flight and the target, and supplemental means interposed between said gun and second named 50 means and automatically operating upon orienting of the gun for correcting the laying of the gun to take account of the inclination of said apparatus due to the distance of the target from the vertical plane through 55 the line of flight.

4. In combination, an aeroplane, a frame mounted thereon for movement about a vertical axis, a second frame mounted in the first frame for movement about a horizontal axis, 60 a cradle carried by the second frame, a gun carried by the cradle, sighting apparatus for the gun including an entry prism, means operatively connected to said cradle and moving said prism in correlation with the gun 65 to provide an angle of elevation, means moving said second frame about its axis thereby imparting an angle of deviation to said gun and sighting apparatus, supplemental means interposed between said gun and last named 70 means giving said second frame and cradle a transverse correction of inclination corresponding to said angle of deviation, said supplemental means including means for varying 75 the transverse displacement of said second frame and cradle for each displacement 80

of the sighting apparatus and gun in elevation.

5. In combination with an aeroplane, a gun mounted thereon, training and elevating means for the gun, sighting apparatus for 75 the gun, means orienting said gun and sighting apparatus into the inclined plane passing through the line of flight and a target located at a distance from the vertical plane through the line of flight, and automatic 80 correction means interposed between said gun and second named means for imparting a correction to the inclination of the gun to take into account the distance of said target from said vertical plane and the variation 85 in said correction as the gun is moved in elevation.

6. Apparatus of the class described, comprising, in combination with an aeroplane, a frame, a cradle and a gun mounted therein, 85 sighting mechanism, a support therefor, an arm having a trunnion operatively connecting the support to said frame, means for moving the arm and cradle simultaneously through an angle of deviation, a graph for 90 indicating the angle through which said support and gun have been moved, means for giving the cradle a transverse correction of 95 inclination corresponding to the angle of deviation of the sighting apparatus, and a ball 100 and socket connection between said last named means and said arm, the inclination given to said cradle bringing the trunnions of the latter out of line with the trunnion on said arm and thereby effecting a transverse displacement of the cradle for each displacement of the sighting apparatus.

7. In combination with an aeroplane, a frame carried thereby and movable about a vertical axis, a second frame carried by the 105 first frame and movable about a horizontal axis, a cradle carried by the second frame for pivotal movement about a second horizontal axis normal to the first horizontal axis, a gun carried in said cradle, sighting 110 apparatus for the gun, means for rotating said second frame, cradle, gun and apparatus as a unit, and means interposed between said first named means and said second frame for moving said second frame, cradle and gun 115 independently of said apparatus.

8. In combination with an aeroplane, a frame mounted thereon for movement about a vertical axis, a second frame pivotally mounted in said first frame, a gun pivotally 120 mounted in the second frame, elevating means for the gun, sighting apparatus for the gun operatively connected with said second frame and including a reflecting prism, means for transversely inclining the second frame independently of said prism thereby imparting an angle of deviation to the gun, and means acting through said inclining means for rotating said prism, second frame 125 and gun simultaneously.

9. An aeroplane gun mount comprising, through an angle of deviation independently in combination with a gun, means mounting of said prism, and means acting through said the gun for universal movement, sighting apparatus including a reflecting prism operationally connected with the gun to maintain a first named means for transversely inclining 10 said gun and prism simultaneously. In testimony whereof I have signed this proper angle of elevation, supplemental laying means for transversely inclining the gun

EUGÈNE SCHNEIDER.
